US0D1076811S

(12) **United States Design Patent** (10) **Patent No.:** **US D1,076,811 S**
(45) **Date of Patent:** **** May 27, 2025**

(54) **OPTICAL CONNECTOR**

(71) Applicant: **Japan Aviation Electronics Industry, Limited**, Tokyo (JP)

(72) Inventor: **Naoki Katagiyama**, Tokyo (JP)

(73) Assignee: **Japan Aviation Electronics Industry, Limited**, Tokyo (JP)

(**) Term: **15 Years**

(21) Appl. No.: **29/853,209**

(22) Filed: **Sep. 14, 2022**

(30) **Foreign Application Priority Data**

Mar. 30, 2022 (JP) ..... 2022-006694 D

(51) **LOC (15) Cl.** 13-03

(52) **U.S. Cl.**

USPC **D13/133**

(57) **CLAIM**

The ornamental design for an optical connector as shown and described.

DESCRIPTION

FIG. 1 is a front elevational view of an optical connector showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof;

FIG. 10 is a perspective view showing a rear, left and top side thereof;

FIG. 11 is an enlarged view of FIG. 1; and,

FIG. 12 is an enlarged view of FIG. 2.

The broken lines shown within the figures illustrate portions of the optical connector that form no part of the claimed design.

1 Claim, 12 Drawing Sheets
